UNITED STATES PATENT OFFICE

2,134,359

SEALED RECEPTACLE

Edward H. Fabrice, Chicago, Ill., assignor to
 Guardian Safety Seal Company, Chicago, Ill.,
 a corporation of Illinois

Application April 18, 1932, Serial No. 605,872
 Renewed November 29, 1937

3. Claims. (Cl. 215—46)

This invention has for its main object to provide a sealed receptacle, such as a bottle and a sealing device for the same, which cannot be unsealed without destroying the sealing cap and wherein the sealing cap is so constructed as to be too difficult and expensive to manufacture in small lots as to make the cost thereof prohibitive to illicit traffickers in refilled bottles and to those who engage in the business of diluting the contents of original packages.

To this end the present invention comprises in combination, a special type of bottle, or other receptacle, equipped with a formation, or formations, for engagement by similar formations on the sealing cap for cooperation to prevent the illegitimate practices hereinabove referred to.

The present invention may be variously embodied as hereinafter particularly set forth and several suitable embodiments thereof are illustrated in the accompanying drawings, wherein:

Fig. 1 is a view in elevation of a sealed receptacle constructed in accordance with this invention.

Fig. 2 is a top plan view of the same.

Fig. 3 is a perspective view of the sealing cap of the receptacle shown in Figs. 1 and 2 prior to applying the same to and securing it to the neck of the bottle.

Fig. 4 is a plan sectional view on the line 4—4 of Fig. 1.

Figs. 5, 6, and 7 are plan sectional views, similar to Fig. 4, illustrating modified embodiments of the invention.

Fig. 8 is a view similar to Fig. 1, showing another embodiment of the invention wherein the type of cap employed differs from that shown in Figs. 1 to 4, inclusive, and wherein the formations of the bottle and cap constituting the essentially novel features of the present invention differ in shape from those shown in Figs. 1 to 7 inclusive.

Fig. 9 is a central longitudinal section view of the bottle neck shown in Fig. 8.

Fig. 10 is a plan sectional view on the line 10—10 of Fig. 8.

Fig. 11 is a view similar to Fig. 9 showing a modified form of sealing cap.

In the structure of Figs. 1 to 7 inclusive, the bottle neck 1 is equipped with a formation 2 adjacent its junction with the body of the bottle, of a non-cylindrical or non-circular type, to receive and engage a similar formation 3 at the terminal of the skirt portion 4 of the bottle cap for cooperation with the said formation 2 to prevent rotation of the cap relatively to the bottle.

Obviously the formation 2 of the bottle neck may

be of any desired shape, contour, and size to perform the desired function efficiently. Preferably said formation 2 of the bottle is of such large size with respect to the outer diameter of the neck as to make the same very prominent in itself and, further, so as to require the portion 3 of the skirt portion 4 of the cap to have its sides of very appreciably longer length than the diameter of the portion 4 thereof and, consequently, thus render the sealing cap too difficult to manufacture to permit small lots thereof to be sold at any less than what may be termed "prohibitive prices."

Preferably the portion 3 of the cap and the formation 2 of the bottle are of a polygonal form, such as substantially a square, as shown in Figs. 1, 3, and 4 which presents protruding corner portions as such present manufacturing difficulties and require expensive dies and first-class metal drawing equipment for their manufacture.

In the instance of Fig. 1, the bottle neck is threaded adjacent its mouth, the threads 6 thereof being spaced from the formation 2 a distance sufficient to accommodate the rip-strip 7 of the cap.

The said cap is, in the instance shown in Fig. 1, of the specific type illustrated and described in United States Letters Patent No. 1,771,034, the terminal portion 3 thereof being added to the structure of said patent.

As shown in Fig. 3, the said cap comprises the crown portion bordered by the knurled bead 8. Below said bead 8 and spaced therefrom and from the terminal portion 3 is an annular bead 9, the portion 10 of said cap disposed between the said beads 8 and 9 being initially cylindrical.

The rip-strip 7 of the cap is bordered by an annular scoring 11 disposed immediately below the bead 9, and by the similar scoring 12 disposed immediately above the terminal portion 3 of the cap. The said scorings 11 and 12 render the rip-strip 7 easily severable from the cap by digital engagement of the terminal tongue 13 thereof which is bordered by an incision extending through the metal of the cap. The said terminal tongue 13 may be of any desired shape but is preferably of one of the several shapes illustrated and described in my Patent No. 1,875,431, issued on September 6, 1932, the specific type herein illustrated being identical with that shown in Figs. 4 and 5 of the drawings of the said pending application. Said tongue may be of the specific type shown in United States Patent No. 1,798,151, if desired.

The said cap, in the form shown in Fig. 3 and containing a suitable packing and sealing disk in

- the crown thereof which is held in place by projection thereof into the bead 8, is placed over the bottle neck with the portion 3 thereof substantially covering the formation 2 of the bottle neck.
- 5 Pressure is now applied to the top of the cap for the purpose of compressing the packing or sealing disk upon the bottle mouth to assure a fluid tight joint and while this pressure is maintained on the said cap, suitable metal spinning means are applied to the portion 10 of the cap to form threads therein to fit the threads 6 of the bottle neck, the threaded portion of which constitutes the mandrel for said spinning operation.

10 The cap is now firmly and non-rotatably mounted upon the bottle neck, the threads 6 of the latter and the threads 14 of the cap preventing relative longitudinal movement between the cap and bottle and the formations 2 and 3 cooperating to prevent rotation of the cap relatively to 15 the bottle.

15 By now tearing out the rip-strip 7, the said cap is severed to permit the crown portion thereof to be rotated relatively to the bottle for removal and replacement of the cap as desired and, upon 20 removing the said cap, the lower end portion of the cap comprising mainly the formation 3 thereof, may be removed.

25 In place of the formations 2 and 3 of the bottle and cap, shown in Figs. 1 to 4, inclusive, formations of other shapes may be employed, a few examples thereof being illustrated in Figs. 5, 6, and 7 and 10, wherein the formations on the bottle neck are indicated by the respective reference characters 15, 17, 19, and 21 and the coating 30 formations at the open ends of the caps are indicated by the reference characters 16, 18, 20, and 35 22, respectively.

30 The caps 23 shown in Figs. 8 to 11, inclusive, correspond with that illustrated and described in the afore-mentioned Letters Patent No. 1,798,151 as to all specific features except the rip-strip 24 thereof which terminates in the tongue 25 corresponding in construction with the tongue of the rip-strip 7 of Figs. 1 and 3. In the 35 cap 23, the sealing cork 26 for the bottle is engaged by formations 27 of the cap which maintain the said cork firmly engaged with the said cap 23. A modified form of the latter is illustrated in Fig. 11 wherein the cap 28 is provided 40 with the extension portion 29 equipped with formations 30 to engage the cylindrical cork 31.

45 The caps 23 and 28, respectively, are equipped at their open ends or lower terminal portions with formations 22 corresponding with the portion 3 of the cap of Figs. 1 to 7, inclusive, except as to 50 specific shape, the same being shown as hexagonal in plane section (Fig. 10) instead of any one of the several shapes shown in Figs. 1 to 7, inclusive, or equivalents thereof, to fit the hexagonal 55 formation 21 of the bottle neck 32. The latter is devoid of threads and in place thereof is provided with an annular bead 33 bordered by annular grooves 34 and 35, respectively, the latter being disposed just above or being bordered by the top 60 face of the formation 21 of said bottle neck.

65 In the case of the structure of Figs. 8 to 11, inclusive, the caps 23 and 28, respectively, are mounted upon the bottle necks and are forced down upon the same and so held while the skirt 70 portions of said caps opposed to the bead 33 and grooves 34 and 35 are spun to fit snugly to the said formations, which serve the same function as the threads 6 of the structure of Fig. 1, to prevent removal of the crown portion of the cap until severance of said cap by removal of the rip- 75

strip 24. In this structure, the lower end portion of the cap remains secured to the bottle neck, the formations 21 and 22 of this structure presenting no advantage other than that of rendering manufacture of a replacement cap difficult 5 and expensive and the further advantage of presenting a bottle and cap easily distinguishable from the conventional type of bottle heretofore commonly used.

10 The aforesaid sealing caps are made, preferably, of sheet aluminum of sufficient thickness to permit the deep drawing thereof required to produce the caps inclusive of the terminal formations thereof without breaking or cracking and without being weakened to such an extent as to be 15 easily cut by a pocket-knife or the like, to enable the portion of the cap shown in Figs. 8 to 11, which remains affixed to the bottle neck, to be removed readily.

20 I claim as my invention:

1. Means for providing a sealed bottle which comprises in combination a bottle having a neck equipped with external thread formations adjacent its mouth and equipped below and spaced from said thread formations with a laterally 25 projecting polygonal formation, and a sheet metal cap comprising a cylindrical body portion adapted to receive telescopically the portion of the bottle neck above said polygonal formation and provided at its lower end with a lateral formation corresponding in shape with and adapted to receive telescopically the polygonal formation of the bottle neck, said polygonal formations of said bottle and cap cooperating to prevent rotation of said cap relatively to the bottle neck, the 30 cylindrical portion of said cap being adapted to be equipped with thread formations engaged with the thread formations of said neck after said cap has been mounted upon the bottle and said threads cooperating with said polygonal formation to prevent relative longitudinal movement between the cap and the bottle neck, whereby a sealed receptacle is provided, said cap being equipped between the thread formations and the polygonal formation thereof with an annular 35 tear-out strip, the removal of which permits the crown portion of said cap to be removed from the bottle for unsealing the latter.

2. The combination with a bottle equipped adjacent the mouth of its neck with thread formations and below said formations with a peripherally non-cylindrical formation constituting an appreciable enlargement of said neck and projecting laterally from said neck, of a sealing cap snugly fitting said neck above said last-named 50 formation composed of non-pliable sheet metal and equipped with thread formations engaged with the thread formations of the bottle neck and equipped at its lower end with a preformed enlarged mouth formation corresponding in shape 55 and size with the said non-cylindrical formation of the bottle neck and telescopically engaged with the latter for holding said cap against rotation relatively to the bottle, said cap being also equipped between the said thread formations and 60 mouth formation with a digitally removable annular strip for effecting severance of said cap thereby to permit the removal thereof from the bottle neck.

3. A sealed receptacle comprising, in combination, a receptacle equipped with a mouth portion equipped with external threads and equipped below the said threads and spaced therefrom with a formation of a non-cylindrical type of minimum cross-sectional dimensions equal to the 75

diametric distance between the crowns of said threads and projecting at a plurality of points farther outwardly from the axis of the receptacle than said threads and presenting appreciable 5 length of peripheral surface area parallel with the axis of the receptacle, and a sealing cap for said receptacle equipped with thread formations engaged with the thread formations of the receptacle and held thereby against longitudinal 10 movement relatively to the receptacle, said cap being equipped with a preformed mouth portion corresponding in shape and size and telescopically

engaged with said non-cylindrical formation of the receptacle for cooperation therewith to prevent rotation of said cap relatively to the receptacle, said cap being equipped between the said preformed mouth portion and the threaded portion thereof with a conventional means for effecting severance of said cap along a plane disposed perpendicularly to its axis, whereby to permit the threaded portion thereof to be removed from the receptacle. 10

EDWARD H. FABRICE.
